ABSTRACT: An amusement device for use with one or more balls consisting of a target cup which is mounted on a playing surface. The target cup comprises an element having an inclined skirt for directing a ball into an elevated receptacle in the form of a depression which is adapted to receive the ball. In use, the ball is projected across the playing surface and rolls up the inclined skirt at a sufficient velocity to come to rest within the receptacle. A variable degree of difficulty is embodied in the device by providing a variable slope in the skirt about the circumference of the cup and by having means to vary the effective depth of the depression, namely a series of annular rings which are removably mounted in the receptacle to form its bottom wall.

TARGET CUP FOR SURFACE PROJECTILES

The present invention relates to amusement devices, and more particularly to a target cup which may be mounted on a playing surface for use with a ball.

It is well recognized that there are many golf putting aids which use cups to assist the golfer in improving his putting skill. Such aids are designed to be used with standard golf balls or balls of similar diameter primarily for the purpose of enabling one who is partially skilled in the game of golf to improve his skill.

The present invention, on the other hand, provides an amusement device which may be adapted to provide a degree of difficulty commensurate with the skill of the players. When the target cup is used with a series of similar cups, the various cups in the series may be modified individually to provide a varying degree of difficulty as the player plays the ball through the series of cups.

More specifically, the present invention provides a target cup of generally dome-shaped configuration having at the top of the dome a receptacle in the form of a depression formed by a series of annular members having a slope opposite to the slope of the body of the cup.

The present invention also insures against inadvertent disassembly of the annular members forming the receptacle by providing an interlock between the members which thereby enables the assembled cup to be handled and stored without fear of disassembly and loss of the elements which are assembled to form the cup.

The particular form of the cup enables it to be stacked with similar cups so as to occupy a minimum of space when not in use.

All of the objects of the invention are more fully set forth hereinafter with reference to the accompanying drawings wherein:

FIG. 1 is a plan view of a game cup embodying the present invention;

FIG. 2 is a view in side elevation of the cup shown in FIG. 1;

FIG. 3 is an enlarged fragmentary inverted plan view illustrating the interlocking between the annular elements of the cup;

FIG. 4 is a greatly enlarged sectional view taken on the line 4-4 of FIG. 1 showing schematically the use of the cup with balls of varying size;

FIG. 5 is a fragmentary sectional view of the cup with its central annulus removed, illustrating the reception of a ball therein; and

FIG. 6 is a detached perspective view of an element of the cup shown in FIGS. 1 through 4.

Referring now to the drawing, the illustrated embodiment of the cup of the present invention is designed to be mounted on a playing surface 10 and comprises a generally dome-shaped body portion 11 which is generally egg-shaped in outline, having a rim providing a circular aperture 12 disposed within the central area of the body portion. The body portion has a continuous thin wall section which slopes upwardly from its outer periphery to the central aperture or rim 12 to provide a continuous skirt surrounding the aperture. As shown in FIG. 2, the slope of the skirt 14 is relatively gradual at the large end of the egg-shaped outline of the body portion and is relatively steep at the narrower end of the body portion, in the present instance the slope varying continuously about the periphery of the body portion. Annular members 15 are mounted in the aperture 12 to provide a receptacle, in the present case a shallow depression depending downwardly into the interior of the dome formed by the skirt 14. In the present instance, the annular members 15 have circular inner and outer peripheries so as to form a series of concentric rings within the aperture 12. The upwardly-facing surfaces 16 of the members 15 are inclined oppositely to the skirt 14 so as to form a dished bottom for the depression within the aperture 12, each surface defining a zone of the bottom wall. In the present instance, there are 4 annular members 15, designated 15-1, 15-2, 15-3 and 15-4 which are releasably interlocked as shown in FIG. 4

to form a four-zoned bottom wall for the depression having a central passageway 17 therein. The passageway is effective to drain the receptacle when the target cup is used out-of-doors and is exposed to the weather.

- 5 When the cup is assembled as shown in FIGS. 1, 2 and 4, the target cup of the present invention may be used with balls of widely varying diameter, as indicated by the broken lines in FIG. 4. The body portion 11 is adapted to rest on the playing surface 10 (FIG. 2) and the player projects the ball with a mallet or club, or manually so that it rolls along the playing surface 10 and up the skirt 14 to rest in the receptacle within the aperture 12. The ball must be impelled toward the target cup 11 with sufficient force to enable it to roll up the surface of the skirt 14, and yet must not have sufficient momentum to roll over the aperture 12 without entering the depression. Furthermore, the propulsion applied to the ball must not be sufficient to carry the ball out of the dished depression after it enters over the lip surrounding the aperture 12. It is apparent that if a ball of large diameter is used, the propulsion of the ball must be accurately controlled to enable the ball to stop within the receptacle of the target cup. By the same token, as the diameter of the ball decreases, the player has more leeway in propelling the ball up the skirt 14 and into the depression, since the smaller diameter of the ball will produce a lesser tendency for the ball to continue rolling out of the depression. In addition to the diameter of the ball, the resiliency of the material composing the ball, and the weight of the ball contribute to the degree of difficulty in causing the ball to come to rest within the receptacle of the target cup. A hard heavy ball obviously will act quite differently from a bouncy light ball. It is contemplated that the standard ball will be in the nature of a standard tennis ball. However, the players, by proper selection of balls, may accommodate the game to the particular skills of the players. For example, when an adult is playing the game with a young child, the difference in skill and coordination between the adult and the child may be compensated for by the players' use of different balls. In this way, the interest in the game may be enhanced by accommodating the difficulty of play with the skill and coordination of the player.

The variable slope of the skirt 14 also contributes to the interest in playing the game. The steeper slope at the small end of the cup creates a greater difficulty in getting the ball to come to rest within the depression and requires the player to exercise sound judgment in selecting the best approach to the cup. This requirement for exercise of judgment further enhances the interest in the game.

- It is contemplated that the game will be played with a series of target cups and that each player must propel his ball into the target receptacle of all of the cups in the series in a particular sequence. The present invention provides means for increasing the degree of difficulty as the player progresses through the series of cups. As pointed out above, the dished bottom 16 of the target depression is formed by the series of annular elements 15 and these elements are selectively removable. When assembled as shown in FIG. 4, the central passageway 17 formed by the inner periphery of the central annular member 15-4 provides substantially no impedance to the rolling of the ball through the depression. When the central annular member 15-4 is removed as shown in FIG. 5, however, the inner periphery of the remaining annular member 15-3 provides an enlarged passageway 17-3 in which the ball may have a tendency to nest. Thus, if in its passage into the receptacle, the ball engages in the passageway 17-3, the passageway will tend to impede its progress and assist in retaining the ball within the receptacle. In similar manner, if the next annular member 15-3 is removed, a further enlarged passageway will be provided by the inner periphery of the next member 15-2, and so forth. When the diameter of the passageway exceeds that of the ball being used by a particular player, it will be relatively easy to cause the ball to come to rest within the receptacle target cup, since the ball will be free to fall through the passageway into the hollow interior of the skirt 14. When all of the annular members 15 are removed,

the passageway is coextensive with the aperture 12 and the game cup affords the minimum degree of difficulty. Thus when using the cups in series, the degree of difficulty may be increased progressively by omitting all of the annular elements 15 in the first cup of the series and successively adding the elements 15-1, 15-2, 15-3, and 15-4 in the succeeding cups. If further variation in the degree of difficulty is desired, the character of the playing surface 10 may be altered between successive cups.

To provide easy mounting and dismounting of the annular members 15, the inner and outer peripheries of the elements 15 are rabbeted, and the periphery of the aperture 12 is likewise rabbeted. In the present instance, the inner peripheries are grooved on the upper side at 20 and the outer peripheries are grooved on the under side at 21 so as to provide a neat interlock between the inner and outer periphery as shown in FIG. 4. Thus a lower flange 22 provided by the groove 20 on the inner periphery may engage in the upper groove 21 formed in the outer periphery of the inwardly adjacent member. Conversely an upper flange 23 on the outer periphery may engage in the groove 20 of the outwardly adjacent member.

In normal use, the weight of the annular elements will maintain them in assembled relation as shown in FIG. 4. However, it may be desirable to prevent inadvertent disassembly of these elements when the cups are removed from place to place and when they are put away for storage. To this end, retaining lugs 24 are provided on the under side of the annular elements 15. In this present instance, the lugs extend from a position flush with the inner periphery of the element under the flange 22 at 25 to the extreme outer periphery of the element at 26, in registry with the outer limit of the flange 23 and spaced below the flange beyond the groove 21. Since the lugs 24 project beyond the groove 21, the inner periphery of each element 15 and of the aperture 12 is provided with cutouts 28 through the flanges 22 which permit the passage of the lugs therethrough to a position below the flange 22. With the lug 24 below the flange 22, the element 15 may be rotated, using the lugs 24 as handholds, to interlock the annular elements. When thus rotated, the lugs 24 on one element 15 engage the under surface of the flange 22 on the outwardly adjacent element 15 and prevent inadvertent disengagement of the two elements.

The lugs 24 also serve as limit stops to limit the relative rotation of the elements 15. Thus as shown in FIG. 3, the outer extremity 26 of the lug 24-4 on the element 15-4 engages against the inner extremity 25 of the lug 24-3 on the element 15-3. By the same token, the outer extremity 26 of the lug 24-3 engages the inner extremity 25 of the lug 24-2. In order to provide a stop against which the lug 24-1 may bear, the body portion 11 is provided with a lug 27 which depends downwardly from the under side of the lower flange of the aperture 22 which may be engaged by the outer extremity 26 of the lug 24-1.

Although a single lug on each annular element 15 may be sufficient to effect the desired interlock, it is preferred to provide three of such lugs in order to facilitate stacking of the target cups when the game is put away in storage. For this purpose, the lugs are spaced substantially equally about the circumference of the annular elements 15 and their lower edges are substantially parallel to the upper surfaces 16 of their associated annular elements. In this way, the lugs of one target cup may rest on the bottom wall of the depression in the downwardly adjacent cup and maintain the target cups in stacked relation.

Thus each lug 24 serves a multiple function, first as a locking element to retain the annular elements in engagement,

second, as a handle for rotating the element 15, third, as an abutment on its element, fourth, as a stop for the abutment of the adjacent element, and fifth, as a stacking leg. Obviously one or more of these functions may be performed by an additional element, or may be omitted, if desired.

Although a particular embodiment of the present invention has been herein illustrated and described, it is apparent that various changes and modifications may be made without departing from the concept of the present invention.

I claim:

1. A game cup for use with a ball comprising a body element adapted to rest on a playing surface and having an internal rim defining an aperture therein, a skirt surrounding said aperture to direct the ball from the playing surface toward said aperture, and means defining a receptacle within said aperture for receiving the ball comprising a series of annular members cooperable to define a depressed annular bottom wall in said receptacle said series including an outer annular member having an outer periphery adapted to be releasably engaged with said rim, an upwardly-facing surface providing a zone of the bottom wall of said receptacle, and an inner periphery defining a passageway smaller than said aperture defined by said rim, and a second annular member having an outer periphery adapted to be releasably engaged with said inner periphery of said first member, an upwardly-facing surface providing a second zone of the bottom wall of said receptacle and an inner periphery forming a passageway smaller than the passageway formed by the inner periphery of said annular member.

2. A target cup according to claim 1 wherein said body element comprises a dome-shaped structure, said rim being elevated therein, said skirt being inclined downward from said rim.

3. A cup according to claim 1 wherein the slope of said skirt varies about the periphery of said body element.

4. A cup according to claim 2 wherein the upwardly-facing surfaces of said annular members which form the bottom of said receptacle are sloped oppositely to said skirt to form a depression within said rim.

5. A cup according to claim 1 including means to releasably interlock said annular members against inadvertent displacement.

6. A cup according to claim 5 wherein the interengaged inner and outer peripheries of said annular members are rabbeted providing grooves and flanges adapted to interengage, and lug means underlying one of the said members adjacent its groove to engage behind the flange of the adjoining member so as to interlock said members and retain said flange in engagement with said groove.

7. A cup according to claim 6 wherein said annular members have circular inner and outer peripheries, said lug means being rigidly mounted on its associated member, the flange of the other member having a cutout means therein to permit passage of the lug therethrough, the circular outline of said peripheries permitting relative rotation of said elements to cause said lug to interlock with said flange at a position circumferentially-spaced from said cutout means.

8. A cup according to claim 7 including stop means on the other member adapted to project into the path of rotation of said lug means to thereby limit relative rotation between said members.

9. A cup according to claim 6 wherein said lug means comprises a plurality of lugs on each member and spaced circumferentially therearound, said lugs having a lower surface parallel to the upwardly-facing surface of their associated member to afford stacking of said cup with similar cups.
